BUILDING BLOCK CONSTRUCTION

Irl R. Cline, Danville, Ill., assignor to Western
Brick Company, Danville, Ill., a corporation of
Illinois

Application April 6, 1939, Serial No. 266,278

4 Claims. (Cl. 72—41)

This invention relates to a new and improved building block and more particularly to a block so constructed as to facilitate an interrupted mortar joint between the inner and outer faces of walls composed of such blocks.

The blocks may be formed of ceramic material or may be made from concrete using any desired material for aggregate such as expanded and burned clay or shale, cinders, crushed stone or gravel. Blocks of this type are formed with opposite faces adapted to form inner and outer wall surfaces, these face portions being joined by cross webs. The cross webs extend vertically to form separated, vertically extending air spaces. The blocks are laid with mortar and this mortar is substantially more pervious to moisture than the blocks themselves. It is highly desirable therefore that the mortar does not extend continuously between the outer and inner wall faces. Excess mortar on the cross webs is not only wasted but has a detrimental effect.

Since such blocks have spaced, narrow, vertically extending meeting ends it is important that these ends be fully bonded by mortar. With usual square meeting faces it is difficult to secure such a bond with the mortar filling the joint flush with the wall faces. Also, if pointing is necessary to secure proper joints there is a tendency for mortar to push through the relatively shallow joint and be wasted.

It is an object of the present invention to provide a new and improved building block.

It is a further object to provide a block provided with cross webs so formed as to prevent a continuous mortar joint between the inner and outer block faces.

It is an additional object to provide a block with end faces formed to facilitate a full mortar joint and to minimize inward flow of mortar in the joint.

It is also an object to provide a block which is simple in design and construction and adapted for commercial production and use.

Other and further objects will appear as the description proceeds.

I have shown a preferred embodiment of my invention in the accompanying drawing in which—

Figure 1 is a plan view of a block;
Figure 2 is a vertical section taken on line 2—2 of Figure 1; and

Figure 3 is a plan view of a series of blocks, partly broken away, showing the vertical mortar joints.

In the drawing, the block is provided with the

wall face portions 11 and the cross webs 12. The webs 12 have their upper portions formed with sloping faces 13 meeting in a line 14 substantially in the plane of the upper faces of the wall portions 11.

The ends 15 of the face portions 11 are shaped upon an outwardly inclined slope or bevel with a vertically extending chamfer or groove 16 formed therein.

In the use of the blocks they are placed in a wall in the position shown in Figure 2, with the pointed or gabled edges of the webs on the upper face of the blocks. In laying the blocks mortar is placed upon both the face portions 11, but none on the cross webs 12. If any mortar is accidentally placed upon the cross webs, the gabled upper edges cause the mortar to drop off and prevent the formation of a continuous mortar joint from the outer to the inner wall face.

Mortar is placed upon the vertical end edges 15 of one block and as the two blocks are brought longitudinally together, due to the slope of these edges 15, the mortar is squeezed outwardly to form a full joint. This minimizes any necessity for pointing the vertical joints, but if any such pointing is necessary, the slope of the edges 15 is such as to compact and hold the mortar in the joint rather than to permit it to pass through and be partially wasted, as would be the case with end edges at right angles to the wall faces. The grooves 16 fill with mortar and increase the effective bond between the mortar and the block besides forming locking keyways for the mortar when it is set.

My improved block, therefore, substantially eliminates the possibility of a continuous mortar joint between the inner and outer wall faces and also provides a more efficient end joint. Both features serve to cut down the labor expense of laying a wall of the blocks and also serve to minimize the amount of mortar required.

While I have shown one preferred embodiment of my invention, this is to be understood to be illustrative only as it is capable of modification to meet varying conditions and requirements and I contemplate such variations as come within the spirit and scope of the appended claims.

I claim:

1. In a building block construction, a unitary block comprising spaced vertically extending wall portions and narrow spaced transverse webs between the wall portions, the webs extending vertically and having upper portions substantially pointed in cross section and located within the contour of the block.

2. In a building block construction, a unitary block comprising spaced vertically extending wall portions and spaced transverse webs between the wall portions, the webs extending vertically for substantially the depth of the wall portions and the upper portion of the webs being gradually reduced in cross section to substantially a line in the plane of the upper faces of the wall portions.
- 5 3. In a building block construction, a unitary block comprising spaced vertically extending wall portions, means connecting the wall portions, the ends of the wall portions being sloped to provide

vertical wall joints between adjacent blocks decreasing in width inwardly from the face of the blocks.

4. In a building block construction, a unitary block comprising spaced vertically extending wall portions, means connecting the wall portions, the ends of the wall portions being sloped to provide vertical wall joints between adjacent blocks decreasing in width inwardly from the face of the blocks, and vertically extending grooves in the ends of the wall portions.

IRL R. CLINE.
